UNITED STATES PATENT OFFICE.

ALBERT PATITZ, OF WEST MERIDEN, CONNECTICUT, ASSIGNOR TO BRADLEY & HUBBARD MANUFACTURING COMPANY, OF SAME PLACE.

DESIGN FOR INKSTAND-HOLDERS.

Specification forming part of Design No. **11,407**, dated September 9, 1879; application filed December 2, 1878.
[Term of patent 3½ years.]

To all whom it may concern:

Be it known that I, ALBERT PATITZ, of West Meriden, in the county of New Haven and State of Connecticut, have invented a new Design for Inkstand-Holder; and I do hereby declare the following, when taken in connection with the accompanying photographic illustration, to be a full, clear, and exact description of the same, and which said illustration constitutes part of this specification, and represents a perspective view.

This invention relates to a design for holder for inkstands, such as consist of a platform on which the inkstands rest, and a rack for the support of pens; and consists in the configuration as hereinafter described, and shown in the accompanying illustration.

The base or platform is of rectangular form, the front at the center having an outwardly curved projection, and at each end a semicircular projection, the extent of the curve of the said projections being less than their corresponding ends of the platform, and so as to form a break at the intersection with their re-

spective ends, as shown in the accompanying illustration.

On the top of the base, at the front center, there is made a triangular-shaped panel or figure, one of the sides corresponding to the front of the platform, the other two running back and meeting at the center, and the said last two sides corresponding to the diagonal position of the inkstands arranged thereon.

The edge of the base may be fluted, as shown, or otherwise ornamented, that ornamentation being no essential part of this design.

On the platform is a pen-rack; but its peculiar form is no part of this design.

I claim—

The design for inkstand-holder, consisting of the platform in rectangular shape, with a curved projection at the front and ends, with a triangular panel at the front center, as described, and shown in the accompanying illustration.

Witnesses: ALBERT PATITZ.
